UNITED STATES PATENT OFFICE.

ARTHUR J. MASON, OF CHICAGO, ILLINOIS.

COAL-MINING MACHINE.

Application filed October 25, 1922. Serial No. 596,758.

My invention relates to certain new and useful improvements in coal mining machines and is fully described and explained in the specification and shown in the accompanying drawings, in which:—

Figure 1 is a side elevation of the machine; Fig. 2 is a plan; Fig. 3 is a side elevation of the forward end of the machine on an enlarged scale; Fig. 4 is a plan view 10 of the parts shown in Fig. 3; Fig. 5 is a longitudinal section on the line 5 of Fig. 6; Fig. 6 is a horizontal section on the line 6 of Fig. 5; Fig. 7 is a longitudinal section on the line 7 of Fig. 4; Fig. 8 is a 15 transverse section on the line 8 of Fig. 3; and Fig. 9 is a transverse section on the line 9 of Fig. 3.

Referring to the drawings, 10 is a track such as is commonly employed in coal mining and upon which run cars, adapted to receive coal, one of which is shown at 11. On the track 10 is a rear truck 12 and a front truck 13, provided with appropriate motors by which they may be driven along 20 the track. The trucks are respectively pivoted by king bolts to a longitudinally extending plate 14, which is centrally perforated and forms a car body or frame. 15 25 is a front supporting-plate and 16 is a rear supporting-plate which overlap each other and are mutually pivoted as shown, and which at their opposite ends ride on slide plates 17 and 18 respectively, said plates being carried by the opposite ends of the 30 plate 14. The front and rear supporting-plates 15 and 16 carry hinges 19 and 20 which serve to support the conveying mechanism. The two halves of the conveying mechanism presently to be described, carry turning 35 motors 21 and 22 provided with sheaves and cables 23 and 24, which run on angles 25 and 26 attached to the plate 14. As either of the motors 21 and 22 is driven, the attached sheave winds itself along the 40 cable, thus forcibly drawing the corresponding half of the conveying mechanism sideways with reference to the plate 14, and causing the corresponding supporting plates 15 and 16 to swing about the pivotal connection formed in the overlapping parts 45 of these plates. In this way either end of the conveying mechanism can be indepen-

dently partially rotated about a vertical center concentric with the central opening in the plate 14.

The rear part of the conveying mechanism is carried by a frame 27. This conveyor is of the ordinary apron type of the form shown and driven by an appropriate motor 28. The conveyor is pivoted to the 55 60 hinges 20 for vertical oscillation.

The frame of the front conveyor is indicated by 29, and it is similarly pivoted for vertical oscillation on the hinges 19. Both the conveyor sections are much 65 heavier at their outer ends than at their adjacent ends, and to cause one part largely to counter-balance the other, they are connected by links 30 and 31 with a longitudinally extending walking beam 32 pivoted 70 on a transverse horizontal pivot carried by the plate 14 immediately below the central opening therein. If it is desired for the purposes of moving the device considerable distances on the tracks to raise 75 the front end of the front section, the front end of the rear section can be elevated and blocked up thus holding the front part of the front section free from engagement with the track on the mine floor, and at the same time depressing the rear end of the 80 rear section so that it will more readily clear overhead obstructions.

The frame 29 of the front section carries an ordinary apron conveyor 33 appropriate 85 driven and running over a front shaft 33^a. The apron delivers the coal upwards and backwards and drops it on the front of the rear section which in turn conveys it into the car, all in an obvious manner; 90 a hopper 34 guiding the coal to the rear conveyor. Since the two conveyor sections rotate in horizontal planes about the same center, and since their two ends are substantially over their mutual center rotation, 95 the discharge of the material from the front and rear conveyor continues properly with the sections in varying angular positions such as are often required in actual work.

The unbalanced weight of the front end 100 of the front conveyor section (amounting to about 1,000 pounds), is carried by a shoe 35 pivotally mounted on the shaft over which the front end of the front conveyor

runs. The shoe has an inclined web 36 extending across the width of the conveyor and two downwardly turned flanges at the ends which ride on the mine floor. The pivotal mounting of this shoe permits it to conform to changes in the angle of the mine floor. Overlying the forward end of the shoe 35 is a reciprocating shoe 37 guided on the shoe 36 by downwardly turned flanges 38 on its edges, terminating at a sharp edge at the front and provided with a plurality of teeth 39 shouldered on their rear faces to form barbs. In operation the reciprocating shoe 37 is violently driven forward underneath the coal to be excavated and relatively slowly retracted, according to present practice at the rate of about twenty times per minute. The reciprocating shoe as it moves forward slides on the inclined web 36 of the shoe 35 so that as its forward edge advances its rear edge falls, the movement closely simulating that which would be produced if the reciprocating shoe swung in an arc of a circle of large diameter with the center 25 above the forward edge of the shoe. In this way the shoe enters under the coal very easily, and with the minimum vertical displacement thereof.

The reciprocating shoe 37 is connected by links 40 with reciprocating bars 41. These bars are adapted to be struck violently by the forward movement of rams 42, the forward ends of which engage directly with the rear ends of the reciprocating bars so as to strike a hammer blow when reciprocated by the mechanism presently to be described. The rams carry between their forward ends a cross shaft 43 which runs in slots in the frame and which is surrounded by slotted 35 links 44 of considerable length, the forward ends of which are carried by the rear ends of the reciprocating bars 41. On rearward movement of the rams to the position shown in dotted lines in Fig. 3 (about 18 inches), the cross shaft 43 moves back idly nearly to the end of its movement, whereupon it picks up the ends of the slotted links 44 and withdraws the reciprocating bars 41 and shoe 37 for a short distance, i. e., from the piston 40 shown in solid to that shown in dotted lines (about 8 inches). While the shoe is thus withdrawn only a short distance, the rams are withdrawn much farther so that when they advance they acquire momentum and strike a hammer blow on the ends of the reciprocating bars thus violently driving the shoe 37 forward.

The rams are spring pressed forward by 60 heavy springs 45 which impart to them their forward impetus. They are retracted by the mechanism best shown at the right hand end of Figs. 3 and 4. 46 is a shaft rotated by an appropriate motor. The rear ends of the rams are link connected by links 47 to this shaft so as to swing only in arcs of

circles of which the shaft is the center. The shaft is provided on its two ends with diametrical arms 48 carrying rollers 49. The reciprocating bars are provided with flat cam surfaces 50 on their rear lower faces, 70 and just in front of these surfaces are curved seats 51. The rotation of the shaft 46 carrying the arms 48 causes engagement between the rollers 49 and the cam surfaces 50 thus elevating the ends of the rams and 75 causing them, through their link connection with the shaft, to swing in a concentric arc upwards and backwards. The rams presently run into the seats 51 exerting a more directly backward pressure and finally, by 80 continued rotation, run out of the seats and free the rams which are forcibly drawn forward by the springs 45.

In order to cushion the forward movement of the rams when the machine is withdrawn and the shoe 37 is not meeting with resistance from the material operated upon by it, the rams are provided on their lower faces with notches 52 which are engaged by hooks 53 spring pressed upward by springs 54 and at their rear ends surrounded by compression springs 55 abutting against stationary plates 56 running through slots in the hooks and carried by the frame of the machine. These hooks are idle except when the rams reach the full forward limit of their possible movement in which case they cushion about the last inch of forward movement thereof, and thus prevent destructive jars to the mechanism. When the shoe is 95 working, as is presently to be described, it is in engagement with the material operated upon and itself takes up the force of the rams and arrests their movement before the hooks come into action.

The mechanism is housed appropriately, the housing, except that provided at the front of the front conveyor section, requiring no detailed description. The housing at the front of the front conveyor has depending plates 57 on the two sides, pivotally mounted on the shaft 33^a which carries the front end of the front conveyor section, and these plates depend substantially to the floor level. Their rear lower ends are connected by a curved cross plate 58 which rests on the floor and carries the weight of the shoe and which, owing to its curvature, slides freely as the front end of the conveyor is swung sideways; and, because of the pivotal mounting, can follow any changes in inclination of the mine floor. This part of the housing serves to prevent coal in which the front of the conveyor will often be buried, from lodging under the front conveyor section, so as either to interfere with the free withdrawal of the machine or to be drawn in and bind under the extreme front end of the conveyor.

Appropriate clutches and motor controls 130

are provided by which the several parts of the machine can be operated at will. These are of conventional form and require no description.

- 5 The operation can now be understood. The machine, although it can be used for the handling of other material, is primarily designed for handling coal which has been under cut and shot according to present 10 practice. The ordinary operation of the under cutting machine leaves a space under the coal of from $4\frac{1}{2}$ to 5 inches in depth, but the lower surface of this space is more or less littered with small particles and dust 15 which is the product of the under cutting machine. When the coal is shot it is quite thoroughly broken up and in the main falls down and rests on the mine floor, its cracks being such that it normally expands enough 20 to take up the space formed by the under-cutting machine, being apparently quite solid, yet in fact, so loosened as to have taken up the extra 4 inches represented by the under cut. There is usually a very distinct crack under the coal body where the 25 mass of the coal is supported by the small particles and dust left by the under-cutting machine. It is at this crack between the loosened coal body and the mine floor that 30 the sharp edge of the reciprocating shoe 37 is directed. The machine is run forward under its own power until the shoe engages the line between the coal and the mine floor where this crack usually exists, 35 and power is maintained to keep the machine constantly pressed forward. The conveyor aprons are started, and at the same time the mechanism for reciprocating the shoe is set in motion. The shoe is thus 40 driven under the coal by powerful hammer blows and is retracted at relatively slower speed. The result of this operation is that the teeth in the shoe constantly rake the lower surface of the coal backwards, being 45 driven under much as a cold chisel would be driven under with powerful blows and slowly retracted to rake out the coal. As 50 a result of this movement, the shoe scrapes for itself a space under the coal, each forward advance drawing more coal over the shoe and crowding that previously removed backwards to the conveyor. While this 55 operation of the shoe is of great importance, it is not by means of the shoe that the bulk 60 of the coal is actually removed. The reciprocations of the shoe constantly withdraw the lower part of the coal, and in addition they keep the whole coal body jarred up and shaking. The machine advances quite 65 rapidly into the coal and presently is substantially buried therein for a distance of two or three feet back of its forward end. Gradually the removal of the lower part of the coal and the jarring of the whole mass causes the superimposed coal to fall
- down, and most of it falls directly onto the conveyor up which it passes very rapidly. The reciprocation of the shoe and the backward dragging action of its teeth are of great importance in dealing with coal in 70 the mine, where the roof prevents the coal from being bodily lifted, and so the coal at the lower edge should be removed to make room for the entrance of the conveyor into the mass. There may, however, be conditions where this retractive action is of less importance, particularly in cleaning up coal which has already fallen down and lies as in a talus slope. Under such conditions the violent hammer blows on the shoe afford a 75 particularly simple means for advancing the conveyor, but the teeth or shoulders would be relatively unimportant.
- The present machine works at great speed, 80 is thoroughly robust and fitted for severe service. It possesses the necessary flexibility to be moved conveniently in a mine and its height is such that it can be handled in the more important mines now in operation without interference with the roof. 85
- I realize that considerable variation is possible in the details of the construction herein shown, and I do not intend to limit myself thereto, except as pointed out in the following claims, in which it is my intention 90 to claim all novelty inherent in the device as broadly as is permitted by the state of the art. I also intend to cover the machine for all of the many uses of which it is obviously capable. 95
- 100 What I claim as new and desire to secure by Letters Patent is:
1. In combination, a movable conveyor having its front adjacent the floor level and means for advancing the same forward to introduce the front end thereof into a body of material to be moved, a thin edged shoe in front of the conveyor and inclined down to the floor level, and means for driving the shoe by successive blows underneath the material to make way for the advance of the conveyor. 105
  2. In combination, a shoe, the front edge of which is adapted to enter under a body of material, and which is provided with a shoulder adjacent the front edge, and means for forcibly advancing the shoe at high speed beneath the material and for retracting the same at lower speed. 110
  3. In combination, a shoe, the front edge of which is adapted to enter under a body of material and which is provided with a shoulder adjacent the front edge, means for forcibly advancing the shoe at high speed beneath the material and for retracting the same at lower speed, and conveying means to the rear of the shoe to receive the material therefrom and convey it to the rear. 115
  4. In combination, a conveying device inclining upward from the floor level, a thin 120

- edged shoe in front of the conveying device adapted to lie on the floor, a pair of spring-pressed rams adapted to engage the shoe to advance the same, and means for repeatedly 5 withdrawing the rams and shoe to the rear and releasing the same to permit them to advance the shoe powerfully under the coal.
5. In combination, a conveying device inclining upward from the floor level, a thin 10 edged shoe in front of the conveying device provided with a shoulder back of its edge and adapted to lie on the floor, a pair of spring-pressed rams adapted to engage the shoe to advance the same, and means for 15 repeatedly withdrawing the rams and shoe to the rear and releasing the same to permit them to advance the shoe powerfully under the coal.
6. In combination, a conveying device inclining upward from the floor level, a thin 20 edged shoe in front of the conveying device adapted to lie on the floor, a pair of spring-pressed rams adapted to engage the shoe to advance the same, a rotatable device having 25 means for engaging the rams to repeatedly withdraw the rams to the rear, and by continuous movement, release the same to be impelled forward to engage the shoe.
7. In combination, a conveying device inclining upward from the floor level, a thin 30 edged shoe in front of the conveying device provided with a shoulder back of its edge and adapted to lie on the floor, a pair of spring-pressed rams adapted to engage the 35 shoe to advance the same, a rotatable device having means for engaging the rams to repeatedly withdraw the rams to the rear, and by continuous movement, release the same to be impelled forward to engage the shoe.
8. In combination, a car frame, two conveying devices thereon overhanging the car frame at opposite ends, the forward conveyor being adapted to discharge onto the rear conveyor, means for swinging each conveyor on a vertical pivot to maintain proper 45 feed relation for the material from one to the other and to permit the operating end of the front conveyor to be swung from side to side, a reciprocating shoe in advance of the end of the front conveyor provided with a thin edge adapted to rest on the floor and means for forcibly advancing the shoe.
9. In combination, a car frame, two conveying devices thereon overhanging the car frame at opposite ends, the forward conveyor being adapted to discharge onto the rear conveyor, means for swinging each conveyor on a vertical pivot to maintain proper 55 feed relation for the material from one to the other and to permit the operating end of the front conveyor to be swung from side to side, a reciprocating shoe in advance of the end of the front conveyor provided with a thin edge adapted to rest on the floor, and with a shoulder back of its edge, and means
- for forcibly advancing the shoe and retracting it.
10. In combination, a car frame, two conveying devices thereon overhanging the car frame at opposite ends, the forward conveyor being adapted to discharge onto the rear conveyor, means for swinging each conveyor on a vertical pivot to maintain proper feed relation for the material from one to the other and to permit the operating end of the front conveyor to be swung from side to side, a reciprocating shoe in advance of the end of the front conveyor provided with a thin edge adapted to rest on the floor, and means for forcibly advancing the shoe 70 and retracting it, the two conveying devices being pivoted for oscillation in vertical planes and being at their adjacent ends mutually connected to a walking beam lever whereby they counterbalance each other.
11. In combination, a car frame with trucks, two plates centrally pivoted to swing about a vertical center, two conveying devices pivotally mounted on said plates to swing in vertical planes thereon, the discharge of the forward conveyor being located over the forward end of the rear conveyor, a walking beam lever pivoted to the car frame and to which the adjacent ends of the conveying devices are mutually 75 pivoted to counterbalance each other, a reciprocable shoe in advance of the front conveyor provided with a thin edge to rest on the mine floor and to be driven under the material and a pair of rams spring-pressed 80 forward and adapted to engage the shoe, and rotatable members provided with rollers to engage the rams to draw the same backward and release the same.
12. In combination, a car frame with trucks, two plates centrally pivoted to swing about a vertical center, two conveying devices pivotally mounted on said plates to swing in vertical planes thereon, the discharge of the forward conveyor being located over the forward end of the rear conveyor, a walking beam lever pivoted to the car frame and to which the adjacent ends of the conveying devices are mutually 85 pivoted to counterbalance each other, a reciprocable shoe in advance of the front conveyor provided with a thin edge to rest on the mine floor and to be driven under the material and a pair of rams spring-pressed 90 forward and adapted to engage the shoe, and rotatable members provided with rollers to engage the rams to draw the same backward and release the same.
13. In combination, a conveying device having its front adjacent the floor level, a thin edged shoe in front of the conveying device adapted to lie at its front edge on the floor, a pair of spring-pressed rams adapted to engage the shoe to advance the 95
- 100
- 105
- 110
- 115
- 120
- 125

- same, a rotatable shaft, links connecting the upper ends of the rams to said shaft, rotatable arms carried by the shaft and provided with contact rollers and cam surfaces on the rams to be engaged by said rollers whereby the rotation of the shaft elevates and draws rearwardly the rear ends of the rams and subsequently releases them to move forward under spring pressure.
- 10 14. In combination, a conveying device having its front adjacent the floor level, a thin edged shoe in front of the conveying device provided with a shoulder back of its edge and adapted to lie with its front edge on the floor, a pair of spring-pressed rams adapted to engage the shoe to advance the same, a lost motion connection between the rams and shoe whereby the rams retract the shoe near the end of their movement, and means for repeatedly withdrawing the rams to the rear and releasing them whereby they alternately draw back the shoe and drive it forward with a hammer-like blow.
- 15 15. In combination, a conveying device inclining upward from the floor level, a thin edged shoe in front of the conveying device adapted to lie on the floor, a pair of spring-pressed rams adapted to engage the shoe to advance the same, means for repeatedly withdrawing the rams and shoe to the rear and releasing the same to permit them to advance the shoe powerfully under the coal, and means for cushioning the rams at the extreme of their forward movement.
- 35 16. In combination, an inclined conveyor, a supporting shoe for the front thereof having a transverse web generally continuing the plane of the conveyor, lateral flanges adapted to rest on the floor, said shoe being pivoted to the conveyor to follow changes in floor inclination, a reciprocating shoe resting at its rear on the said first-mentioned shoe and having a thin front edge resting on the floor and means for driving said reciprocating shoe forward.
- 40 17. In combination, an inclined conveyor section, a reciprocating shoe at the front thereof, and provided with a thin edge adapted to rest on the floor, means for reciprocating said shoe, a housing pivoted to the conveyor section adjacent its front end depending therefrom and having a cross plate to provide a laterally slid able support for the housing and adapted by reason of the pivotal support of the housing to follow changes in inclination of the floor.
- 45 18. In combination, a conveyor having its front adjacent the floor level, a thin edged shoe at the front thereof inclining downward from the end of the conveyor to the floor and adapted to be forced under the material to be moved, means to advance the shoe with reference to the conveyor and to lower its rear edge as it is moved and means to advance the conveyor to follow up the advance of the shoe.
- 50 19. In combination, a conveyor having its receiving end adjacent the floor level, a receiving shoe inclined downwardly therefrom, a reciprocating shoe thin edged at the front and slidably supported at the rear on said receiving shoe and having its forward edge free to follow the floor and means for advancing the reciprocating shoe and for advancing the conveyor to follow up the shoe.
- 55 20. The herein described method of introducing the lower end of a conveyor beneath a body of previously under-cut and shot coal which consists in forcing an inclined shoe under the coal in advance of the conveyor by hammer blows.
- 60 21. The herein described method of removing loosened coal previously under-cut and shot which consists in repeatedly forcing a shoe, thin edged at the front and provided with a shoulder behind the edge underneath the loosened body of coal along the smooth surface formed by the under-cutting machine and alternately retracting the shoe to drag back the coal resting upon it.
- 65 22. The herein described method of removing loosened coal previously under-cut and shot which consists in repeatedly forcing a shoe, thin edged at the front and provided with a shoulder behind the edge underneath the loosened body of coal along the smooth surface formed by the under-cutting machine and alternately retracting the shoe to drag back the coal resting upon it and conveying away the coal which passes over the rear of the shoe.
- 70 75 23. The herein described method of introducing the lower end of a conveyor beneath a body of previously under-cut and shot coal which consists in forcing an inclined shoe provided with a rearwardly facing shoulder under the coal in advance of the conveyor by hammer blows and alternately retracting the shoe to withdraw the coal immediately upon it.
- 80 85 90 95 100 105 110 115 120 125 24. In combination, a car frame, two conveyors extending therefrom in opposite directions, the front conveyor adapted to remove matter and discharge it to the rear conveyor, means for pivoting said conveyors to maintain substantially continuous alignment between the rear of the front conveyor and the front of the rear conveyor, a walking beam pivoted to the car frame, a connection between the walking beam and the rear of the front conveyor and a connection between the walking beam and the front of the rear conveyor, whereby the conveyors counterbalance each other.
- Witness my hand and seal this 3rd day of October, 1922.
- ARTHUR J. MASON. [L. S.]
